UNITED STATES PATENT OFFICE.

ELMER H. WILKINSON, OF DETROIT, MICHIGAN, ASSIGNOR TO THE JEWETT RADIO AND PHONOGRAPH CO., OF DETROIT, MICHIGAN, A CORPORATION OF MICHIGAN.

DESIGN FOR A RADIOCABINET.

Application filed December 17, 1924. Serial No. 11,733. Term of patent 3½ years.

To all whom it may concern:

Be it known that I, ELMER H. WILKINSON, a citizen of the United States, residing at Detroit, in the county of Wayne and State of Michigan, have invented a new, original, and ornamental Design for Radiocabinet, of which the following is a specification, reference being had to the accompanying drawing, forming part thereof.

The figure is a perspective view of a radio cabinet embodying my new design.

I claim:

The ornamental design for a radiocabinet as shown.

ELMER H. WILKINSON.
